UNITED STATES PATENT OFFICE

124,983

DESIGN FOR A CHENILLE JACKET

Charles Shapiro, New York, N. Y.

Application March 13, 1940, Serial No. 90,886

Term of patent 3½ years

To all whom it may concern:

Be it known that I, Charles Shapiro, a citizen of the United States, residing in New York, New York, have invented a new, original, and ornamental Design for a Chenille Jacket, of which the following is a specification, reference being had to the accompanying drawings, forming a part thereof.

Fig. 1 is an elevation of the front of the chenille jacket showing my new design.

Fig. 2 is an elevation of the back thereof.

I claim:

The ornamental design for a chenille jacket, as shown.

CHARLES SHAPIRO.
